Inventor:

N. P. Lathrop
by S. W. Beadle, atty.

United States Patent Office.

W. P. LATHROP, OF WEST WINSTED, CONNECTICUT.

Letters Patent No. 92,196, dated July 6, 1869.

IMPROVEMENT IN KNIFE-HANDLE BOLSTER.

The Schedule referred to in these Letters Patent and making part of the same.

To all whom it may concern:

Be it known that I, W. P. LATHROP, of West Winsted, in the county of Litchfield, and State of Connecticut, have invented a new and improved Knife-Handle Bolster; and I do hereby declare that the following is a full and exact description of the same, reference being had to the accompanying drawings, and to the letters of reference marked thereon.

This invention relates to an improved method of attaching the blades of ordinary case-knives to their handles; and consists mainly in a peculiar construction of the bolster, whereby greater strength and durability are obtained, as will hereinafter more fully appear.

In the drawings—

Figure 1 is a side elevation of a knife, provided with my invention;

Figures 2, 3, and 4, are perspective views of the parts detached; and

Figures 5 and 6, sectional views of the bolster B.

To enable those skilled in the art to make and use my invention, I will proceed to describe its construction and operation.

A represents the blade, with its tang *a*; B, the bolster; and C, the handle.

The bolster B consists of the two side plates, *b*, connected by the solid hub *b'*, in which is the milled slot *b²*, which extends entirely through the same, forming a suitable orifice for the tang *a* to enter.

On the inside of the hub *b*, is the mortise *c*, into which is fitted a corresponding tenon, *c'*, on the ends of the handle C.

This latter is also cut away on each side, as shown, to fit the space between the side plates and bolster.

d d represent lips, which project on each side of the slot *b²*, and are sufficiently far apart, to admit the inner end of the knife-blade between them, which fits closely therein, and has a shoulder on the back, formed by placing the tang near the centre of the blade, which shoulder bears against the end of the hub *b'*, thus relieving the strain from the tang, and causing it to bear on the bolster.

The method of attaching the parts is as follows:

The handle is fitted to the bolster as described, and the tang introduced in a suitable orifice, passing first through the slot in the bolster, and cemented therein. The inner end of the blade will then fit closely between the lips *d d*, and bear against the end of the hub *b'*. An orifice is then made through the side plates of the bolster, handle, and tang, and a pin or rivet introduced, which securely fastens the whole.

The bolster may be of cast or malleable metal, and may be applied to a solid handle, or to scale-tang cutlery.

The orifice in the handle for the reception of the tang, is commonly burned out, which chars the wood at the end, and weakens it where considerable strength is required. I form said orifice by suitable machinery, and thereby obviate this difficulty.

The mortise *c* in the bolster is particularly calculated to make an edge-bearing for the handle, and prevent the same from splitting.

The projecting lips *d d* afford great strength, when side-pressure is brought to bear on the blade, and the shoulder *o*, bearing as it does against the end of the hub *b'*, makes a firm bearing, obviating all strain on the tang.

The whole arrangement is one combining strength, neatness, and utility, and is especially adapted to carving and butchers' knives, and also to table-cutlery.

Having thus fully described my invention, What I claim as new, and desire to secure by Letters Patent, is—

1. The bolster B, having the slot *b²*, lips *d d*, mortise *c*, and side plates *b*, connected by the hub *b'*, substantially as and for the purpose specified.

2. In combination with the above, the handle C, with its tenon *c'*, substantially as described.

This specification signed and witnessed, this 25th day of May, 1869.

W. P. LATHROP.
